CLAIM

I claim the ornamental design for a handle, as shown and described.

DESCRIPTION

FIG. 1 is a perspective view of the handle design;

FIG. 2 is a top plan view thereof;

FIG. 3 is a bottom plan view thereof;

FIG. 4 is a rear elevational thereof;

FIG. 5 is a front elevational view thereof; and,

FIG. 6 is a left side elevational view thereof, which is also a mirror image of the right side elevational view.
